C. D. HILL.

PUMP.

APPLICATION FILED JAN. 4, 1912.

1,072,613.

Patented Sept. 9, 1913.

UNITED STATES PATENT OFFICE.

CHARLES D. HILL, OF ROCHESTER, NEW YORK, ASSIGNOR TO JUDD & LELAND MFG. CO., OF CLIFTON SPRINGS, NEW YORK, A CORPORATION OF NEW YORK.

PUMP.

1,072,613.

Specification of Letters Patent. Patented Sept. 9, 1913.

Application filed January 4, 1912. Serial No. 669,318.

To all whom it may concern:

Be it known that I, CHARLES D. HILL, of Rochester, in the county of Monroe and State of New York, have invented a new and useful Improvement in Pumps, which improvement is fully set forth in the following specification and shown in the accompanying drawings.

The present invention relates to air pumps and more particularly to that type in which a plurality of communicating cylinders of different sizes is employed for the purpose of effecting a greater compression of the air; and an object of the invention is to provide a construction in which the method of assembling its parts has been simplified so that the time required for such assembling is reduced to a minimum, thus reducing the cost of manufacture of the pump.

To these and other ends the invention consists in certain parts and combinations of parts all of which will be hereinafter described, the novel features being pointed out in the appended claims.

In the drawings: Figure 1 is a side view of a pump constructed in accordance with this invention; Fig. 2 is an enlarged section on the line *a—a* Fig. 1; Fig. 3 is an enlarged section on the line *b—b* of Fig. 1; Fig. 4 is a vertical section through the upper part of two cylinders on the line *c—c* of Fig. 3; Fig. 5 is a vertical section on line *d—d* of Fig. 3; and Fig. 6 is an enlarged vertical section through the base on a line *e—e* of Fig. 2.

In the present embodiment of the invention there are employed three cylinders 1, 2 and 3 which are supported at their lower ends on a common base 4. The base is preferably formed midway between its ends with an upstanding boss 5 having in this instance three sockets 6, 7 and 8. The upper portions of the walls of these sockets are preferably internally threaded at 9 and, below the threaded portion, are provided with annular grooves 10 the lower walls of which are inclined downwardly and project inwardly beyond the threaded portion to provide shoulders 11. The lower ends of the cylinders 1, 2 and 3 are externally threaded and engage the threaded walls of the sockets, their extreme lower ends being forced into tight engagement with the shoulders 11. The grooves 10 are provided in order that the threads may be properly formed so

that the ends of the cylinders may reach the shoulders 11, for it must be apparent that threads could not be found on the walls of the sockets in close proximity to the shoulders. The base 4 may also serve to establish communication between the cylinders 1 and 2, and, to this end, said base is provided with a port 12 connecting the sockets 6 and 7. A port 13 may also lead from the socket 8 to a nipple 14 to which the flexible piping 15 is connected. The upper ends of the cylinders may be connected by a tie piece 16 having three openings whose diameters correspond with the external diameters of the cylinders, in order that said tie piece may fit tightly about the cylinder walls, being soldered or otherwise secured thereto. This tie piece may also serve to establish connection between the upper ends of two of the cylinders and to this end the internal walls of the openings, through which two of the cylinders pass, are provided with annular grooves 17 and 18 connected by a port 19 and respectively communicating with ports 20 and 21 provided in the cylinders 2 and 3.

It is apparent that air from the cylinder 2 passes, by way of port 20, to groove 17, thence through port 19 to groove 18, and, from the latter, through port 21 into cylinder 3. With a communication, of the type described, between the upper ends of the two cylinders 2 and 3, it is unnecessary that the ports 20 and 21 shall occupy any definite relative positions. This permits the use of screw threads for connecting the cylinder with the base 4, and said cylinders may be turned on the base until they have been firmly and tightly secured thereto without taking into consideration the positions of their upper ends.

The upper ends of the cylinders may be closed by plugs 22 having packing glands 23 through which the piston rods 24 operate, said rods having their upper ends connected by a single handle 25. The pistons 26, 27 and 28, provided respectively in the cylinders 1, 2 and 3, are preferably formed of leather cups acting in one direction to compress air and in the other direction to permit air to pass the same. The pistons 26 and 28 compress the air within their cylinders on the downward stroke, while the piston 27 compresses the air within its cylinder on the upper stroke, so that the piston

27 acts in a direction opposite to that of the pistons 26 and 28.

Within the depressions of the base 4 may be provided centrally arranged bosses 9 which project upwardly in order to coöperate with the ends 30 of the piston rods projecting from the pistons. This arrangement prevents the operator of the pump moving the pistons so far downwardly within the cylinders that said pistons will engage the bottoms of the compression chambers and injure said pistons.

It is apparent that air, drawn in the upper end of the cylinder 1 through the port 31, 15 will pass below the piston 26 upon the upward movement of the latter, so that, on the downward movement of the piston, air will be forced by said piston through the port 12 into cylinder 2 and past the piston 27. 20 Upon the next upstroke of the pistons, the piston 27 will force the air from the cylinder 2 into the cylinder 3 at the upper end of the latter, and past piston 28 by way of port 19, so that upon the downward movement of the 25 pistons, the piston 28 will force the air from the nipple 14. Of course, as the air passes from one cylinder to another it becomes more highly compressed.

From the foregoing it will be seen that 30 there has been provided a structure which is strong and durable in use and may be manufactured very economically. The labor of assembling the parts is reduced to a minimum, as it is not necessary to accurately 35 locate the cylinders in any definite positions. Air tight joints between the cylinders and the base which connects them are formed, as the lower ends of the cylinders are forced firmly against shoulders.

40 What I claim as my invention and desire to secure by Letters Patent is:

1. In a pump, the combination with a pair of cylinders each provided with a port, of a member surrounding the cylinders and having annular grooves communicating with the ports and with each other.

2. In an air pump, the combination with a base and a pair of cylinders attachable thereto by a rotary movement, said cylinders 50 being provided with ports near their upper ends, of oppositely-acting pistons in said cylinders connected together for simultaneous movement, and a tie piece about the cylinders at the ports, said tie piece having internal grooves communicating with the ports and with each other.

3. In an air pump, the combination with a base having three sockets, two of which communicate with each other and a discharge

nipple communicating with the other socket 60 through said base, of three cylinders of different diameters having screw threaded engagement with the inner walls of the sockets, all of said cylinders having ports near their upper ends, a tie piece having separate openings each receiving one of said cylinders, the walls of two of the openings being provided with grooves which communicate with each other and with the ports in the two cylinders, the port of the other cylinder being 65 open to the atmosphere, cup shaped pistons operating in the cylinders, one of said pistons acting in a direction opposite to the others, and a handle common to all of the pistons.

4. In an air pump, the combination with a base having sockets therein, the inner walls of said sockets being provided with screw threads near their outer ends, and grooves below the screw threads, the lower wall of 80 each groove being inclined downwardly and projected inwardly beyond the screw threads, of cylinders engaging the screw threads and the inclined walls, pistons operating in the cylinders, and common operating 85 means for the pistons.

5. In a pump, the combination with a base having a socket internally threaded near its outer end and provided with a groove below the socket, the lower wall of 90 the groove being inclined downwardly and projecting inwardly beyond the screw threads, of an externally threaded cylinder engaging the threads of the socket and having its end abutting the lower wall of the 95 groove, and a piston operating in the cylinder.

6. In a pump, the combination with a base having sockets therein and centrally arranged bosses projecting upwardly within 100 the sockets, the walls of the sockets being provided with screw threads near their outer ends and grooves below the threads, the lower wall of each groove being inclined downwardly and projected inwardly beyond 105 the screw threads and above the upper ends of the bosses, and the base having ports leading from the sockets above the bottoms of the latter but below the upper ends of the bosses, of cylinders engaging the screw 110 threads and having their lower ends abutting the inclined walls, pistons operating in the cylinders, and common operating means for the pistons.

CHARLES D. HILL.
